ATTORNEY

UNITED STATES PATENT OFFICE.

WILLIAM E. McLAUGHLIN, OF MIDDLETOWN, OHIO, ASSIGNEE TO THE BARKELEW ELECTRIC MANUFACTURING COMPANY, OF MIDDLETOWN, OHIO, A CORPORATION OF OHIO.

DIMMING APPARATUS.

Original application filed November 25, 1925, Serial No. 71,309. Divided and this application filed April 1, 1926. Serial No. 99,171.

My invention relates to a dimming apparatus and, in particular, to an apparatus to be installed on cars employing two filament bulbs or separate dimming bulbs without a 5 resistance, and is a division of my application filed November 25, 1925, Serial No. 71,309.

It is the object of my invention to provide a switch which may be applied to existing 10 cars or which may be originally applied on automobiles as factory equipment, which may be used on cars which do not have a resistance in their main switch or elsewhere but which employ for dimming purposes bulbs 15 with two filaments or two separate bulbs.

It is a further object to provide a switch and wiring which can be readily attached to the existing electrical equipment of a car and which can be operated by the foot of the 20 operator, as his hands are already fully employed.

In the accompanying drawings:

Figure 1 is an elevation of the switch installed on a floor board with the floor board 25 and cover of the switch shown in section, the side walls of the cover being removed;

Figure 2 is a section on the line 2—2 of Figure 1;

Figure 3 is a section on the line 3—3 of 30 Figure 1;

Figure 4 is an elevation of the switch showing the cover elevated to permit of access to the switch;

Figure 5 is a view similar to Figure 1 35 showing the switch button and associated mechanism in depressed position;

Figure 6 is a bottom plan view of the switch mechanism;

Figure 7 is a perspective of the switch 40 plunger and contact members;

Figure 8 is a section on the line 8—8 of Figure 2;

Figure 9 is a wiring diagram showing the switch on the dash board of a car in position to burn the lights brightly with the operating plunger of the dimming switch up, at which time the lights are bright;

Figure 10 is a similar view showing the dimming switch in depressed position and 50 the lights dim;

Figure 11 is a view similar to Figure 9 save that the night lights are normally dim

because the switch on the dash board is thrown into dimming position;

Figure 12 is a similar view to Figure 11 55 with the switch plunger depressed so that the lights are bright;

Figure 13 is an elevation of the switch with the cover removed showing the plunger in its uppermost position and the contact 60 fingers on the other side from that side shown in Figure 1; and

Figure 14 is a similar view to that shown in Figure 13, showing the plunger depressed.

Referring to the drawings in detail, 1 is 65 the floor board of a vehicle which is constructed to receive the supporting screws 2, the lower ends of which are threaded through the cover plate 3, which has a supporting cup 4. A U-shaped sliding cover 5 closes 70 the open sides of the supporting cup and has its top resting on top of the cover plate 3, an aperture 6 being provided in the sliding cover 5 to permit of the passage of the stem 7, which carries the foot button 8 on 75 the upper end thereof. This button is detachable and the stem itself is adapted to be extended in sections.

The supporting cup 4 carries on its base a plate of insulating material 9 which is provided with depressed grooves 10 for receiving the flat base 11 of the several contact fingers. These bases of the contact fingers are limited in their inward position by a square portion 12 in the center of which is 85 a plunger aperture 13. 14 is the base plate. The bases of the spring fingers are held in position by the screws 15 which constitute the terminal screws which carry on their outside ends below the supporting cup the usual 90 washers 16, nuts 17 and locking washers 18 for clamping the cables thereto. Surrounding the stem 7 is a helical spring 19, one end of which rests on the cup 4 while the other end abuts against the insulated plunger 20, 95 which carries a plurality of segmental contact rings 21, 23 and 25 disposed at different elevations and on different portions of the periphery of this insulated plunger 20.

As will be seen in Figures 1, 2, 4 and 5, 100 the contact fingers 22 and 22' both engage the segmental contact ring 23 when that ring and the plunger are in their uppermost position. The insulated plunger with its con-

tact rings is caused to move downwardly by the foot of the operator and is limited on its return or upward movement by the cotter pin 24 passing through the stem 7 just above the insulated plunger 20. The contact ring 23 is slotted to receive the contact finger 22^a which always remains in engagement with it. Upon the depression of the insulated plunger 20, as in Figure 5, it will be noted that the contact ring 23 remains in engagement with the finger 22^a, but becomes dis-engaged from the finger 22. The finger 22 engages the segmental contact ring 25. This segmental ring 25 extends around the other side of the insulated plunger 20 where it is adapted to engage with a contact finger 26 when the plunger is depressed. The segmental ring 23 extends in the other direction around to the other side of the insulated plunger 20 where it is adapted to engage with the contact finger 27 when the plunger is depressed.

When the insulated plunger 20 is in its elevated position, as in Figure 13, showing its other side of the switch, the contact ring 21 is in engagement with the fingers 26 and 27, and, in Figure 14, it is dis-engaged but the depression of the plunger has connected with fingers 26 and 27 the rings 25 and 23 respectively so that the fingers 26 and 22 are both in engagement with the ring 25 when the plunger is depressed and fingers 27 and 22^a are in engagement with the ring 23 when the plunger is depressed.

Referring to the electrical diagram, 29 is a ground for the wire 30 which is connected to a battery 31. This battery is connected by the wire 32 to the switch terminal 33 on which is pivoted a switch arm 34 adapted to engage with the contact 35. This contact is connected by the wire 36 to the spring finger of the switch, designated 22^a, in the position shown. This finger is connected by the contact ring 23 to the contact finger 22, which is, in turn, connected by the wire 37 which, in turn, is connected to the wire 38 and is connected to the bright lamp 39. On its other side, it is connected by the wire 40 to the other bright lamp 41. Each of the lamps is grounded by the grounds 42 and 43.

The other side of the circuit is provided with a contact 44 from which leads a wire 45 to the contact finger 26. The other contact finger 27 is connected by a wire 46 to the small or dim lamps 47. In these diagrams the heavy line indicates the contact ring which is actuated.

Thus, in Figure 9, the ground 29, wire 30, battery 31, wire 32, terminal 33, switch arm 34, contact 35, wire 36, contact finger 22^a, contact ring 23, contact finger 22^a, wire 37, wires 38 and 40, bright lamps 39 and 41 and grounds 42 and 43 are in circuit.

In Figure 10, the lights are dim because the circuit consists of the ground 29, wire 30,

battery 31, wire 32, terminal 33, switch arm 34, contact 35, wire 36, contact finger 22^a, contact ring 23, contact finger 27, wire 46, dim lamps 47 and grounds 42 and 43.

In Figure 11, which lights are normally dim, the circuit consists of ground 29, wire 30, battery 31, wire 32, terminal 33, switch arm 34, contact 44, wire 45, contact finger 26, contact ring 21, contact finger 27, wire 46, lamps 47 and grounds 42 and 43. 75

In Figure 12, the circuit consists of ground 29, wire 30, battery 31, wire 32, terminal 33, switch arm 34, contact 44, wire 45, contact finger 26, contact ring 25, contact finger 22^a, wire 37, wires 38 and 40 to lamps 39 and 41 and grounds 42 and 43. 80

It will be obvious that if the operator throws his switch existing on the car for bright lights, he may cause the lights to be dimmed by depressing the stem and insulated plunger of the foot switch, but, if he carries his lights normally dim with his switch in that position, as in Figures 11 and 12, he can brighten his lights by depressing the stem and insulated plunger of the foot switch. 85 90

When I refer to bright and dim, I include filaments of same intensity but so located that one in focus will throw the light a greater distance than the one out of focus. 95 Such terms as bright and dim will be so understood in the claims.

It will be understood that I desire to comprehend within my invention such modifications as may be necessary to adapt it to varying conditions and uses. 100

Having thus fully described my invention, what I claim as new and desire to secure by Letters Patent, is:

1. In combination, a switch consisting of a supporting means, a plurality of contact fingers carried thereby, insulating means for supporting said fingers, a reciprocatory member adapted to reciprocate adjacent said fingers and a plurality of contact rings mounted on said reciprocatory member for connecting said contact fingers in varying combinations, one of said contacts always connecting a pair of said fingers so that there is always a closed circuit, guides on one of said contact rings to engage one of said contact fingers to guide said reciprocatory member and means to support said supporting means beneath the floor board of a vehicle and a foot actuated member adapted to be connected to said reciprocatory member, whereby the foot of an operator of a vehicle may operate the switch. 105 110 115 120 125

2. In combination, a switch consisting of a supporting means, a plurality of contact fingers carried thereby, insulating means for supporting said fingers, a reciprocatory member adapted to reciprocate adjacent said fingers and a plurality of contact rings mounted on said reciprocatory member for 130

- connecting said contact fingers in varying combinations, one of said contacts always connecting a pair of said fingers so that there is always a closed circuit, guides on 5 one of said contact rings to engage one of said contact fingers to guide said reciprocatory member and means to support said supporting means beneath the floor board of a vehicle and a foot actuated member adapted 10 to be connected to said reciprocatory member, whereby the foot of an operator of a vehicle may operate the switch, said contact rings being spaced from one another at different elevations and being segmentary, 15 they are disposed on different positions on the periphery of the reciprocatory member.
3. In a switch, a supporting cup, a cover plate, a sliding cover, a reciprocatory plunger working in said cover plate and 20 cover, and supporting cup, yielding means to move said plunger in one direction and an insulating member carried thereby, a plurality of segmental rings spaced from one another disposed about the periphery of the 25 insulating member, a plurality of contact fingers of varying heights adapted to be connected together by said contact rings in varying combinations according to the position of the insulating member, one of said 30 segmental rings always connecting a pair of said fingers, so that there will always be a closed circuit, and means to maintain the insulating member in a predetermined position on the plunger.
- 35 4. In combination, in a switch consisting of a support, an insulating supporting plate, a plurality of contact fingers arranged about a given center having inwardly extending contact portions, said fingers being of requi- site height and lengths of contact portions 40 to engage contact members, reciprocating therebetween, contact members of which one is always in engagement with a pair of said fingers, an insulating member carrying said contact members and a spring-pressed 45 plunger carrying said insulating member, said contact members being arranged at different heights on said insulating member at different points around the periphery of said insulating member. 50
5. In combination, a switch having a plurality of contact fingers, a member adapted to reciprocate adjacent said fingers, a plurality of contacts on said member for engaging said fingers in varying combinations, 55 one of said contacts always connecting a pair of said fingers so that there is always a closed circuit, guides on one of said contacts on said reciprocating member to engage one of said contact fingers and guide said reciprocating member and means for actuating said member. 60
6. In combination, a switch having a plurality of contact fingers, a member adapted to reciprocate adjacent said fingers, a plurality of contacts on said member for engaging said fingers in varying combinations, 65 one of said contacts always connecting a pair of said fingers so that there is always a closed circuit, and remaining in connection 70 therewith until after another contact engages a pair of fingers, guides on one of said contacts on said reciprocating member to engage one of said contact fingers and guide said reciprocating member and means for 75 actuating said contacts.

In testimony whereof, I affix my signature.
WILLIAM E. McLAUGHLIN.
